UNITED STATES PATENT OFFICE.

WILLEM DIEPERINK-LANGEREIS, OF WARREN, PENNSYLVANIA.

DESIGN FOR AN ARTIFICIAL CHRISTMAS TREE.

Application filed January 29, 1924. Serial No. 8,476. Term of patent 14 years.

To all whom it may concern:

Be it known that I, WILLEM DIEPERINK-LANGEREIS, a citizen of the United States, and a resident of Warren, in the county of Warren and State of Pennsylvania, have invented a new, original, and ornamental Design for Artificial Christmas Trees, of which the following is a specification, reference being had to the accompanying drawing, forming part thereof.

The figure is a perspective view of an artificial Christmas tree, showing my new design.

I claim:

The ornamental design for an artificial Christmas tree, as shown.

WILLEM DIEPERINK-LANGEREIS.
